UNITED STATES PATENT OFFICE.

ROBERT M. CHRISTENSEN, OF RACINE, WISCONSIN.

RADIATOR CORE.

Application filed June 3, 1920. Serial No. 386,808.

To all whom it may concern:

Be it known that I, ROBERT M. CHRISTENSEN, a subject of the King of Denmark, and resident of Racine, in the county of Racine 5 and State of Wisconsin, U. S. A., have invented new and useful Improvements in Radiator Cores, of which the following is a description, reference being had to the accompanying drawings, which are a part of 10 this specification.

The present invention relates to certain new and useful improvements in radiators, and more especially to that type employed in connection with water cooled internal 15 combustion engines in which the heated water is supplied to an upper water chamber, and flows downwardly through substantially vertically trending water passageways to a lower water compartment from which the 20 water is supplied to the engine, the vertical water passageways being separated by a plurality of substantially transverse air passageways through which the cooling fluids pass and have contact with the walls of the 25 water passageways to reduce the temperature of the water in its passage therethrough.

This invention is designed to provide a radiator of the class described which will 30 efficiently cool the water in its passage through the vertically trending water passageway and has for one of its objects to provide air passageways which are inclined with respect to the horizontal so that the 35 current of air passing through will be deflected with full force against the walls of the vertically trending water passageways forming the air passageways whereby the 40 efficient cooling thereof is obtained.

My invention has for another of its objects to provide a radiator of the class described in which the air passageways are 45 substantially diamond shape, whereby a greater area of the outer surface of the water passageway is exposed to the cooling fluids and whereby the length of such water passageway is considerably increased.

This invention has for a further object to provide means dividing each air passageway and having tapering substantially V-shaped projections on opposite sides to split or divide the air and thus better insure its contact with the entire wall area of the air passageways.

With the above and other objects in view 55 which will appear as the description proceeds, my invention resides in the novel con-

struction, combination and arrangement of parts substantially as hereinafter described and more particularly defined by the appended claims, it being understood that such 60 changes in the precise embodiment of the herein disclosed invention may be made as come within the scope of the claims.

In the accompanying drawing I have illustrated one complete example of the physical 65 embodiment of my invention constructed according to the best mode I have so far devised for the practical application of the principles thereof, and in which:

Figure 1 is a front view of a portion of 70 a water cooling radiator embodying my invention;

Figure 2 is a fragmentary sectional view taken on the line 2—2 of Figure 1;

Figure 3 is a fragmentary sectional view 75 taken on the line 3—3 of Figure 2; and

Figure 4 is a fragmentary sectional view taken through the radiator at substantially 80 right angles with respect to Figure 3, on the line 4—4 of Figure 2.

As is common in radiator constructions employed for use in cooling the water supplied to the water jackets of internal combustion engines, my improved radiator comprises an upper water compartment, a lower 85 water compartment, substantially vertically trending water passageways connecting the upper and lower water compartments, and a plurality of air passageways between the 90 water passageways for cooling the same and reducing the temperature of the water as it passes therethrough.

In the accompanying drawing but a portion of a radiator is shown, and in such drawing the numeral 5 designates the upper 95 water compartment, 6 the substantially vertically trending water passageways connecting the upper water compartment 5 and the lower compartment (not shown), and 7 the plurality of air passageways disposed between the water passageways.

The present invention relates more particularly to the radiator core members which form the water and air passageways, and consists of lengths of flattened tubing or the like arranged in pairs and provided with a plurality of opposed angular bends or corrugations 8 providing the substantially diamond shape air passageways 7. As best shown in Figure 3, the core members of each 105 pair have their innermost bends 9 abutting and secured together in any desired man-

ner, and the adjacent members of each adjacent pair have their outermost angular bends in register and securing therebetween inserts 10, to be later described.

5 The points where the core members abut are slightly flattened to provide a better connection therebetween, and this assures a rigid construction. The angular corrugations or bends in the core members are 10 inclined downwardly and forwardly with respect to the horizontal, whereby currents of air entering at the front thereof, will be deflected against the portions of the core members forming the bottom walls of the 15 air passageways and thus insure the contact of the cooling fluids with the walls forming the water passageways.

In former constructions employing the substantially horizontal air passageways, 20 the contact of the cooling fluids with the walls forming the air passageways is not positive, and oftentimes will barely contact therewith. My construction eliminates this difficulty as the downward inclination of the 25 air passageways insures the positive engagement of the air currents, and furthermore creating a current whereby the air will be re-bounded or deflected to the upper walls of the passageways.

30 An advantage in shaping the air passageways as disclosed in the drawing is that the length of the water passageways is considerably increased as well as the cooling area, and when the corrugations are less pronounced, this advantage is not obtained.

The inserts 10 form cooling fins, and at the same time have projections 11 struck therefrom, or otherwise formed on opposite sides thereof, in line with the air passageways to divide the currents of air passing therethrough and insure the more positive contact of the air with the entire wall area 40 of the passageways 7.

The projections 11 are substantially V-

shaped, tapering or diverging rearwardly 45 to divide the air in two, causing part to be deflected to the upper wall area and part to the lower wall area, the entire air being deflected somewhat to the side. The 50 openings 12, formed by the projections serve to permit the passage of a portion of the air currents from one side of the inserts to the other and thus set up eddying currents.

From the foregoing description taken in 55 connection with the accompanying drawing it will be at once apparent to those skilled in the art to which an invention of this character appertain that I have provided a 60 radiator construction which is efficient and practical for the purpose described.

What I claim as my invention is:

1. A radiator construction comprising a plurality of core members providing substantially vertically trending water passageways, and bent to form substantially horizontal, upwardly and rearwardly inclined air passageways extending between the water passageways, and an insert dividing each air passageway and having means 65 for breaking the air passing therethrough and deflecting the same to engage the entire wall area of the air passageways.

2. A radiator construction comprising a plurality of core members providing substantially vertically trending water passageways, and bent to form substantially horizontal, upwardly and rearwardly inclined air passageways extending between the water passageways, an insert dividing 75 each air passageway, and substantially V-shaped projections carried by the opposite sides of each insert for deflecting the air against the walls of the air passageways.

In testimony whereof, I affix my signature.

ROBERT M. CHRISTENSEN.
